UNITED STATES PATENT OFFICE.

CLEMENT LEE DOWNEY, OF CINCINNATI, OHIO.

TYPE-WRITER ATTACHMENT.

No. 902,566.

Specification of Letters Patent.

Patented Nov. 8, 1908.

Application filed September 14, 1905; Serial No. 278,516.

To all whom it may concern:

Be it known that I, CLEMENT LEE DOWNEY, a citizen of the United States, residing at Cincinnati, in the county of Hamilton and State of Ohio, have invented certain new and useful Improvements in Type-Writer Attachments, of which the following is a specification.

My invention broadly relates to a means automatically actuated by a type-writer to indicate on the writing sheet the variations in the spacing.

My invention more particularly relates to an attachment to a type-writer having the general construction, function and objects of the device shown in my former patent No. 698,469, granted April 29, 1902, on addressing attachment for type-writers.

I have only shown so much of the machine in the present drawings as will serve to illustrate the purpose and the operation of my new attachment.

This machine is designed to print a series of addresses upon a long transcript sheet, which is then taken to a machine where impressions are taken from the printing. The transcript sheet is fed from a supply roll to the action of the type-writer and wound upon a receiving roll.

I have found that the variation in spacing inherent in friction feeds is such as to render it practically impossible to duplicate upon the impression machine the spacing or intermitting feed of the transcript sheet through the type-writer, and it is the purpose of this invention to provide an attachment for the type-writer which will be automatically actuated by the carriage movement to make a physical impression upon the transcript sheet, which impression will serve in coöperation with the mechanism of the impression machine, to duplicate the spacing of the transcript sheet in the type-writer. As illustrated this physical impression is a punched hole, though it may be a notch, indentation, embossing or other physical change wrought in the transcript sheet.

The various features of the invention will be more fully set forth in the description of the accompanying drawings, making a part of this specification, in which:

Figure 1 is a rear elevation. Fig. 2 is a section on line α , α , Fig. 1. Fig. 3 is a de-

tail, partly sectional view of the attachment. Fig. 4 is a top plan view of the 55 attachment.

1 is the type-writer frame having the usual carriage 2, and platen roll 3, the reciprocating and spacing mechanism not being shown.

4 represents the supply roll upon which is wound the transcript sheet 5, which passes around the platen and is wound upon the receiving roll 6.

7 is a bracket attached to the rear of the 65 frame of the carriage, it is provided with the male and female punch members 8, 9, the spring actuated female member 9 being adapted to be reciprocated vertically to engage the die 8.

10 represents a resilient strip of metal between members 8 and 9, having an orifice through which passes the die 8, the purpose of which strip is to free the sheet from the male punch member. Pivoted to said bracket 75 is a lever 11 the upper end of which is adapted to engage the lower end of punch 9, the lower end of said lever has an adjustable screw 12 adapted to be brought against an abutment or the frame of the machine when 80 the carriage is shifted to the initial end of its travel whereby the punch is actuated. The transcript sheet passes between said punch members just before it engages the platen roll. By these means the transcript sheet is 85 punched whenever the carriage engages the lever 11 against the frame.

13 represents a guide bar over which the paper passes in order to be properly fed to the punch.

Having described my invention, I claim:

1. In combination with a type-writer frame, carriage, and platen roll, and means for feeding a transcript sheet onto the platen roll, male and female punch members supported upon the carriage between which said transcript sheet passes, and means actuated by the carriage movement to reciprocate one of said punch members, substantially as described.

2. In combination with a type-writer frame, carriage and platen roll, a bracket attached to the carriage carrying male and female punch members between which a transcript sheet passes, means for feeding said 105 sheet onto the platen roll, and a lever for re-

22
ciprocating one of said punch members, said lever being adapted to be engaged against an abutment when the carriage is moved to punch the said transcript sheet when a line is written and the said roll is spaced, substantially as described.

3. In combination with a type - writer, a punch adapted to be automatically actuated by the carriage at the end of its movement to

impart an impression to the transcript sheet, substantially as described.

In testimony whereof, I have hereunto set my hand.

CLEMENT LEE DOWNEY.
